UNITED STATES PATENT OFFICE.

WILLIAM E. WINTERS, OF ONEIDA, NEW YORK.

JOURNAL-BEARING.

1,288,348.

Specification of Letters Patent. Patented Dec. 17, 1918.

Application filed January 11, 1916. Serial No. 71,565.

To all whom it may concern:

Be it known that I, WILLIAM E. WINTERS, a citizen of the United States, and a resident of Oneida, in the county of Madison and State of New York, have invented a certain new and useful Journal-Bearing, of which the following is a specification.

This invention relates to journal boxes, and has for its object a journal box provided with a lubricating means which journal box is particularly simple in construction, economical in manufacture, and highly efficient and durable in use. Other objects appear throughout the specification. The invention consists in the combinations and constructions hereinafter set forth and claimed.

In describing this invention, reference is had to the accompanying drawings, in which like characters designate corresponding parts in all the views.

Figure 1 is a longitudinal sectional view of one embodiment of my journal bearing.

Fig. 2 is a sectional view on line A—A, Fig. 1.

Fig. 3 is a sectional view on the plane of line B—B, Fig. 1, the contiguous parts of the hanger for the bearing being also shown.

Fig. 4 is a fragmentary plan view of parts seen in Fig. 3, the lubricator being omitted.

This journal box is preferably divided into upper and lower sections 1 and 2, the dividing line between which extends lengthwise of the journal opening of the box. The lower section 2 is provided with means for lubricating the shaft between the ends of the box, and means is provided at opposite ends of the box for removing the oil from the shaft at the ends of the box, in order that the oil will not flow out of the box along the shaft.

As here shown, the lower section 2 is formed with oil reservoirs or recesses 3 at its opposite ends and with a lengthwise channel 4 opening through the journal or shaft opening of the box and also at its ends into the recesses 3. These recesses 3 are enlarged in cross-section, as seen in Fig. 2, with respect to the shaft opening, and the bottoms thereof are below the bottom of the channel 4, so that each recess is capable of receiving and holding a considerable amount of oil. As seen in Fig. 4 one of these recesses is formed with a lateral extension 5 which is open at its top for receiving the lubricator to be described.

6 and 7 are upper and lower sections of a sleeve located in the box sections 1, 2 and

around the shaft 8, the lower section 7 being formed in two sections, the edges of which are spaced apart and form a slot 9 in which a wick 10 extends in order to engage the periphery of the shaft 8. The intermediate portion of the wick is held off the bottom of the channel 4 by a suitable spacing member 11 including a portion spaced apart from the bottom of the channel in order to form a feed passage 12, said portion being also provided with ducts 13 at intervals through which the lubricant may feed to the wick. The end portions of the wick extend through eyes or loops 11' at the ends of the strip 11. Said spacing member 11 is here shown as a strip in the form of an inverted channel U shape in cross-section, the ends of the legs of the U bearing on the bottom of the channel and the intermediate portion supporting the wick and being formed with the ducts 13. The wick 10 absorbs the oil from the passage 12 through the ducts 13, especially when the ends of the wick have become clogged by sediment.

In order to prevent the oil from working out through the crevices between the upper and lower sections 1, 2 by capillary action, the opposing surfaces 14, 15 of the sections 1, 2 are arranged to diverge outwardly and upwardly, these diverging surfaces meeting, at their inner lower ends laterally extending surfaces 16, provided on the sections, 1, 2, the spaces between the said surfaces 14, 15, being closed at their upper ends by horizontally extending surfaces 17 provided on one of the sections 1, 2, and here shown as provided on the upper section 1.

Means is provided within the recesses 3 for removing the oil from the shaft 8, so that the oil will not pass out the ends of the box beyond the packings 18. These means are here shown as wipers 19 carried at the ends of springs 20 which are fixed at corresponding ends 21 to side walls of the recesses 3, and have looped portions carrying at their ends the wipers 19. These wipers 19, are arranged to engage the lower side of the shaft so that the oil removed therefrom falls into the recesses 3. In order to prevent the oil from working past the wipers and along the upper section 1, the upper section 1 is formed with internal parallel grooves 22 which provide ribs 23, the faces of which are opposed to but spaced from the shaft 8, far enough to prevent the oil from working along the shaft by capillary action.

24 is a lubricator for supplying oil to one of the recesses 3, the lubricator having a depending hollow stem 25 which extends through the open top of the extension 5 and 5 rests upon the bottom of one of the recesses 3, this stem having an outlet 26. The construction of the lubricator forms no part of this invention.

27 designates a hanger or other support 10 for the journal box, said hanger having means as screws 27^a arranged at angles of 90° to the axis of the bearing, and the box is provided between its ends with sockets having arc-shaped surfaces 28 with which 15 the screws 27^a engage, these surfaces being located at 90° angles with respect to the axis of the shaft, that is they are arranged in pairs on diametrically opposite sides of the box and the diameters connecting the pairs 20 intersect at a right angle. The arc-shaped surfaces 28 and the screws or other means 27^a on the hanger constitute means by which the journal box can adjust itself in alignment with the shaft. For example, when 25 the shaft is being hung, the journal box is placed approximately in position and the shaft rotated. The rotation of the shaft will cause the bearing box to seek its axis and when the axis thereof is found, the 30 screws 27^a are tightened against the surfaces 28.

In the operation of my bearing, the oil is fed from the lubricator to one of the recesses 3 and from there is carried by the 35 wick into the other recess 3, the channel 4 maintaining the oil at the same level in both recesses 3. During the rotation of the shaft the wipers 19 remove oil from the shaft at the end of the bearing box.

40 What I claim is:

1. A bearing comprising a box formed with a journal opening, an oil recess at one end of the opening and with a lengthwise channel opening into the recess and also 45 opening along one side into the journal opening, a wick extending lengthwise of the channel and into the recess, and means for holding the wick off the bottom of the channel against the shaft journaled in the box, substantially as and for the purpose specified.

2. A bearing comprising a box formed with a journal opening, an oil recess at one end and with a lengthwise channel opening 55 into the recess and also opening along one side into the journal opening, a wick extending lengthwise of the channel and into the recess, and means for holding the wick off the bottom of the channel against the shaft in the box, said means having a portion spaced apart from the bottom of the channel and formed with feed passages, substantially as and for the purpose set forth.

65 3. A bearing comprising a box formed

with a journal opening, an oil recess at one end, and with a lengthwise channel opening into the recess and also opening along one side into the journal opening, a wick extending lengthwise of the channel and into 70 the recess, and spacing means for holding the wick off the bottom of the channel against the shaft in the box, said spacing means comprising a strip in the general form of an inverted U in cross section, the 75 strip having feed ducts through the intermediate portion thereof, substantially as and for the purpose described.

4. A journal bearing comprising a box formed with a journal opening, recesses at 80 its opposite ends and with a channel extending lengthwise of the box and opening along one side into the journal opening, and at its ends into said recesses, a wick located in the channel and having its opposite ends extending into the recesses, and means for holding the wick off the bottom of the channel, said means including a portion spaced apart from the bottom of the channel whereby a feed passage is provided below said 85 portion, substantially as and for the purpose specified.

5. A journal bearing comprising a box formed with a journal opening, and with a lengthwise channel opening along one side 95 into the journal opening, a bushing located in the journal opening and formed with a slot alined with the channel, a wick located in the slot, and means for holding the wick off the bottom of the channel including a 100 portion spaced apart from the bottom of the channel whereby a feed passage is provided beneath said portion, and means for supplying oil to the wick, substantially as and for the purpose described.

105 6. A bearing comprising a box formed with a journal opening, recesses in its opposite ends and a channel extending lengthwise of the journal opening and communicating at its ends with the recesses and opening 110 along one side into the journal opening, a bushing located in the journal opening and having a slot alined with the channel, a wick extending lengthwise of the slot and having its ends depending into the recesses, means 115 for holding the intermediate part of the wick off the bottom of the channel, including a portion spaced apart from the channel whereby a feed passage is provided beneath said portion, and a lubricator for supplying 120 oil to one of the recesses, substantially as and for the purpose specified.

7. A journal bearing comprising a body formed with a journal opening, recesses at the opposite ends of the opening, the box 125 being composed of upper and lower sections, wipers located in the recesses and engaging the lower side of the shaft for removing oil from the shaft, and the upper section being formed with parallel grooves which provide 130

ribs extending around the upper side of the shaft, the faces of the ribs terminating close to the shaft, and being spaced from the shaft far enough so that the oil will not work by 5 capillary action along the shaft, the ribs and the grooves preventing the oil from passing along the upper section of the jour-

nal box, out the ends of the box, substantially as and for the purpose set forth.

In testimony whereof, I have hereunto 10 signed my name, at Oneida, in the county of Madison, in the State of New York, this 10th day of Nov., 1915.

WILLIAM E. WINTERS.
